UNITED STATES PATENT OFFICE

2,442,605

PROCESS FOR THE CONSTRUCTION OF
TIGHT SCREENSAndré Paul Jourdain, Brussels, Belgium, assignor
to Compagnie Internationale des Pieux Armés
Frankignoul, Société Anonyme, Liege, BelgiumApplication April 1, 1946, Serial No. 658,646
In Belgium August 29, 1942

9 Claims. (Cl. 61—58)

1

The construction of tight screens of reinforced concrete or the like, with great resistance to bending, ground thrusts and vertical stress, has not been effected satisfactorily by the processes known hitherto, especially when the work is carried out in hard ground.

It has already been suggested to construct screens by means of pile planks made of concrete, prepared in advance and partially or completely surrounded by sectional irons, especially T or U irons, arranged so as to leave, between the consecutive pile planks, a certain space which is filled with concrete during or after the extraction of the sectional irons delimiting this space. This connection made of unrammed concrete, which has the same thickness as the pile planks, does not establish a perfect weld between the pile planks and forms a zone of less resistance in the screen, especially to bending and ground thrusts; moreover, it does not increase the resistance to vertical stress. The sectional irons are quickly damaged and make this process practically inapplicable in hard ground.

It is also well known how to construct screens of pile planks moulded in the ground by means of caissons sunk edge to edge in the ground and withdrawn as the concreting takes place. These caissons, which generally have a rectangular cross-section and are guided only on one side, are easily deformed and damaged so that this method cannot be applied in resistant ground. Moreover, the injection of water into the ground cannot be used to facilitate the sinking, because this water would dilute the concrete of the pile planks which have just been made.

The invention renders it possible to eliminate the disadvantages of the well-known methods and to construct with ease, even in hard ground, perfectly tight screens with a greatly increased resistance to horizontal stress and to bending, and at the same time with great resistance to vertical stress, in contrast to the well-known methods.

The invention also makes it possible to limit to the strict minimum the hold to be given to the pile planks properly speaking, owing to the fact that these pile planks ensure only a small portion of the screen's resistance to bending and horizontal stress; this resistance is ensured for the greater part by the foundation posts which the screen comprises, in accordance with the invention, and which can reach great depths.

According to the invention, the connection of two consecutive pile planks is effected by means of a post, preferably of reinforced concrete,

2

moulded in the ground by means of a sinking tube, this post having a diameter considerably greater than the thickness of the pile planks, and effectively embedding the abutments of the adjacent pile planks.

Also according to the invention, the tubes are sunk from distance to distance and the pile planks are then sunk between these tubes while being guided by guides provided on the tubes so as to ensure guidance of the pile planks at their two ends which prevents accidental deviations and facilitates their correct placement. Each tube is therefore sunk independently, at a certain distance from the preceding tube and from the last pile plank which has been placed, which makes sinking in hard ground possible, even by using injection of water, without risk of damaging the part of the screen already completed.

The desired diameter of the post and the perfect embedding of the abutments of the contiguous pile planks can be obtained by vigorous ramming of the concrete through the inside of the tube while it is being withdrawn, so as to press the concrete sideways into the ground outside the cross-section of the tube. According to the invention one can also use tubes which have a diameter considerably greater than the thickness of the pile planks and which embrace the abutments of the pile planks so that they become embedded by the mere casting of concrete, and the concrete is pressed against the ends of the large surfaces of the pile planks when the concrete is rammed through the inside of the tube.

In view of the fact that in accordance with the invention veritable foundation posts are inserted in the screen, the latter's resistance to vertical stress is very much greater than that of screens constructed according to the well-known methods. These posts can be constructed in the most difficult ground. The tubes required for making the posts can be sunk to great depths in relation to the length of the pile planks constituting the screen, which makes it possible to give the screen a perfect anchoring and to increase its carrying capacity. It is already well known how to give greater length to certain pile planks of a screen. The sinking of pile planks prepared in advance, either of rectangular caissons for moulding pile planks, or of sectional irons embracing pile planks, can, however, not be carried to great depths without causing damage to them, and it becomes practically impossible in resistant ground. These disadvantages do not exist for posts used in accordance with the invention.

Certain examples of performing the invention

are described hereunder with reference to the attached drawing in which:

Figs. 1 and 2 show plans of two phases in the construction of a screen;

Figs. 3, 4, 5, 7 and 8 show several variants of performing the invention;

Fig. 6 shows a cross-sectional view along the line VI—VI in Fig. 5; and

Figs. 9—12 show plans of four phases of another method of constructing a screen.

In the example according to Figs. 1—2, the posts are constructed by means of round tubes 1 provided with longitudinal guides each constituted by a groove formed by a sectional iron 2 into which the plane or curved side surface of a pile plank will enter.

At first the tubes 1 are sunk into the ground by some well-known process, at such a distance from each other that the distance between the guides corresponds to the width of a pile plank. Then a pile plank 3 prepared in advance, e. g. of reinforced concrete, is slipped into the guides of the two tubes and driven to the desired depth by means of some appropriate method, e. g. by being driven or by the injection of water, or by a combination of these two methods.

A reinforcement 4 can then be placed in the first tube and concrete can be rammed into it while the tube is progressively withdrawn so that a post 5 is formed which can be provided with an extended base. The tube withdrawn is then sunk on the other side of the second tube, whereafter a second pile plank is placed and the second post concreted. The operations described above are subsequently repeated. As a result a screen of indefinite length can be constructed by means of two tubes only.

According to the invention, real sinking tubes are thus used to construct foundation posts, i. e. strong metal tubes which can be used almost indefinitely and can be sunk in all kinds of ground, even to very great depths, and which make it possible to apply any method of sinking, especially the very advantageous sinking process by means of a preferably heavy ram striking on an adhesive plug of concrete or the like formed inside the lower end of the tube. This process makes it possible to achieve a much greater sinking power than has been possible to obtain until now in the well-known processes of constructing pile plank screens.

The ramming of the concrete poured into the tube should be sufficiently vigorous to press the concrete sideways so that it fills also the cavities formed in the ground by the guides 2 and embeds completely the abutments of the pile planks, the post formed having a diameter considerably greater than the thickness of a pile plank. The roughness of the post also increases the stability of the screen.

The guidance of the pile planks between the tubes can be effected in any manner whatever. In the example shown in Fig. 3, the tubes have projections or ribs 6 which co-operate with grooves 7 provided in the side surfaces of the pile planks.

As shown in Fig. 4, instead of being placed in alignment, the pile planks can form a certain angle between each other. To this effect, a tube is used on which the guides have a corresponding angular position (Fig. 4).

Each pile plank which is to be sunk, is separated by a tube and a pile plank, i. e. a distance practically exceeding one metre, from the last concreted post which is therefore safe from any ef-

fect of the water injected. This process of sinking makes it possible to use less heavily reinforced pile planks and thus to save much steel as they need not be subjected to the powerful strokes of the usual battering.

Figs. 5 to 8 show various forms of the sinking tube which make it possible to compress the concrete directly against the edges of the large surfaces of the pile planks so as to improve the tightness and the resistance of the joints connecting the pile planks.

The tube 8 according to Figs. 5—6 has a diameter considerably greater than the thickness of the pile planks 3 and has two longitudinal grooves 9 for guiding the pile planks. As the tube thus really embraces the pile planks, a perfect envelopment of their abutments is obtained, even by the mere casting of concrete through the tube, but more especially if the concrete poured into the tube is rammed vigorously. It will be of advantage to use a ram of a form similar to that of the tube. It is also useful to give the abutments of the pile planks a rounded or bevelled shape (see Fig. 7) and to shape the grooves 9 accordingly.

If the tube 8 is placed on a sinking point 10 of metal or concrete sunk into the ground and also covering the cross-section of the hollow guides 9, these will be empty, at least in certain soils, at the moment when the pile planks are introduced, which facilitates the sinking of the pile planks as well as the extraction of the tube, while it improves the weld between the concrete of the post and the pile planks.

Fig. 7 shows a tube 11 having two longitudinal dents which give the tube a cross-section in the shape of an 8. Angle irons 12 welded to the tube serve as guides to the pile planks whose bevelled abutments engage with the dents of the tube.

Fig. 8 shows a sinking appliance formed by two coupled tubes 13, 14 in each of which operates a drop hammer.

It goes without saying that, without departing from the spirit of the invention, the sinking appliance envisaged by the invention can have greatly varied forms of construction.

In conclusion, it should be noted that the invention is also applicable to the construction of screens of pile planks moulded in the ground. It is sufficient to replace each pile plank 3 by a normal caisson 15 for the moulding of pile planks in the ground, as shown in Fig. 9. The caisson is filled with concrete (Fig. 10) and is then withdrawn, leaving a pile plank 16 in the ground between the tubes 1 (Fig. 11). The latter are then withdrawn and the posts concreted as described above (Fig. 12). The guiding of the caissons at their two ends prevents their deviation and the risk of damage which would result from it. In this case also the insertion of posts in the screen increases its resistance and makes its construction in hard ground possible.

What I claim is:

1. In a process for the construction of tight screens in the ground by means of pile-planks of concrete and like materials, driving in abutting relation and alternate succession into the ground pile-planks and sinking tubes having a diameter greater than the thickness of the pile-planks, pouring pile material into each driven tube and ramming this material while withdrawing the tube so as to press the material sideways for effectively embedding the abutments of the adjacent pile planks.

2. In a process for the construction of tight screens in the ground by means of pile planks

driven into the ground, driving sinking tubes by pairs into the ground at a distance from each other corresponding to the width of a pile plank, driving a pile plank in abutting relation between each pair of tubes, pouring pile material into the tubes and withdrawing the latter while ramming the pile material so as to form a pile having a diameter considerably greater than the thickness of the pile planks and effectively embracing the abutments of the adjacent pile planks.

3. In a process for the construction of tight screens in the ground, driving into the ground, at a certain distance from each other, sinking tubes having outer longitudinal guiding means, engaging between the opposing guiding means of each pair of sinking tubes a pile-plank of concrete and like materials having a thickness substantially smaller than the diameter of the tubes, driving the pile-planks into the ground, pouring pile material into the tubes and withdrawing the latter.

4. In a process for the construction of tight screens in the ground, driving into the ground, at a certain distance from each other, sinking tubes having outer longitudinal guiding means, engaging between the guiding means of each pair of tubes a tubing caisson for moulding a pile-plank having a thickness substantially smaller than the diameter of the tubes, driving the caissons into the ground, moulding the pile-planks in the ground, withdrawing the tubing caissons, pouring pile material into the tubes and withdrawing the latter.

5. In a process according to claim 3 said outer longitudinal guiding means consisting of longitudinal grooves forming guides for the pile planks.

6. In a process according to claim 3 the steps of first placing into the ground at a certain distance from each other sinking points intended to be left in the ground and each having a larger cross section than said sinking tubes and covering also the cross section of said outer longitudinal guiding means; and thereafter placing on said sinking points said sinking tubes.

7. A sinking tube for molding in the ground piles of concrete and like materials between the successive pile planks of a screen, said tube comprising in combination a tubular member being open at both ends; and oppositely arranged external longitudinal guiding means on said tubular

member having a width being smaller than the diameter of said tubular member and extending substantially from one end thereof to the other so as to be adapted to embrace the abutments of adjacent pile planks.

8. A sinking tube for molding in the ground piles of concrete and like materials between the successive pile planks of a screen, said tube comprising in combination a tubular member being open at both ends; and oppositely arranged external longitudinal grooves in the wall of said tubular member, said oppositely arranged longitudinal grooves having a width being smaller than the diameter of said tubular member and extending substantially from one end thereof to the other so as to be adapted to embrace the abutments of adjacent pile planks.

9. A sinking tube for molding in the ground piles of concrete and like materials between the successive pile planks of a screen, said tube comprising in combination a tubular member being open at both ends; oppositely arranged external longitudinal guiding means on said tubular member having a width being smaller than the diameter of said tubular member and extending substantially from one end thereof to the other so as to be adapted to embrace the abutments of adjacent pile planks; and a sinking point at one end of said tubular member having a larger cross section than that of said tubular member and covering also the cross section of said external longitudinal guiding means.
